UNITED STATES PATENT OFFICE.

ROBERT KUNICKE, OF BAD OEYNHAUSEN, GERMANY, ASSIGNOR TO N. BERNARD PERRETZ, OF CHICAGO, ILLINOIS.

RAIL CONNECTION FOR RAILWAY TRACKS AND THE LIKE.

Application filed August 28, 1923. Serial No. 659,730.

This invention relates to a new and improved rail connection for railway tracks and the like. In the making of tracks for railways and the like steel rails are used and these rails are placed end to end, the adjacent rails being connected together. In view of the fact that these rails expand and contract with variations in temperature, it is necessary in connecting adjacent rails together to provide a space between the abutting ends so as to permit this expansion and contraction. This constitutes a serious defect, for as the wheels of the locomotive and cars run along the track they must pass across this space or gap in passing from one rail to another, and this causes the end of the rail to be injured and also is injurious to the wheels and injuriously affects the easy riding of the cars. This also creates unnecessary noise. The present invention has among other objects to provide a rail connection which will obviate these difficulties.

Referring now to the drawings:

Fig. 1 is a side elevation of one form of rail connection embodying the invention.

Fig. 2 is a plan view of the rail connection shown in Fig. 1.

Fig. 3 is a sectional view through the rail having a projection thereon, at the point where the bolt nearest the end passes therethrough.

Like numerals refer to like parts throughout the several figures.

Referring now to the drawings, I have shown for purposes of illustration the ends of two rails 1 and 2 with the space 3 between them. One of these rails is provided with the overlapping part 4 which overlaps a portion of the other rail. A portion of the ball of this other rail is preferably removed or omitted, as shown in Figs. 1 and 2. The overlapping portion 4 is preferably integral with the rail with which it is associated and at one end thereof. The face of the projecting portion 4 and the face of the portion of the ball of the rail cut away, are inclined from the central portion of the rail outwardly, so that the cross space 3 between the rails consists of two sections at an angle to each other, both extending part way across the ball of the rail. By having the opposed faces of the part 4 and the rail inclined, a smaller space between these parts can be provided, and still permit the necessary relative longitudinal movement of the rails due

to variations in temperature. This is due to the fact that the two inclined faces do not move directly toward each other, but part of the movement is a relative longitudinal movement between the two faces. The overlapping portion 4 is connected with the ball of the rail and preferably has a web 5 which connects it with the base 6 of the rail, as clearly shown in Figs. 1 and 3, there being a space between the web 5 and the web of the rail for the plate 7 which connects the rails together. There is a plate 8 on the other side of the rails and these plates are connected to the rails in any suitable manner as by means of the bolts. The web 5 is provided with a suitable opening 10 for one of these bolts 9.

It will be seen that with this construction when the wheel passes from one rail to the other across the space 3 it is not required to leave one rail before engaging the other as it will engage the overlapping portion 4 of one of the rails when it passes over the space 3 and will continue to engage this overlapping portion 4 during a portion of its engagement with the other rail. It will thus be seen that there will be a smooth passage of the wheel from one rail to the other and that injury to the rails and to the wheels will be prevented as will also unnecessary noise.

It will further be seen that the variation of the width of the space 3 due to expansion and contraction will in no manner affect the result as the overlapping portion 4 will always overlap a portion of the rail 1 and act to transfer the wheel from one rail to the other, smoothly and without jar.

It will be noted that the ends of the adjacent rails are uneven and that the space between them is divided into two sections at an angle to each other.

I have described in detail a particular construction embodying the invention, but it is of course evident that the parts may be varied in many particulars without departing from the spirit of the invention as embodied in the claims hereto appended, and I therefore do not limit myself to the particular construction shown.

I claim:

1. A rail connection for railway tracks comprising two rails adapted to have their ends abut with a space between them, a portion of the ball of one rail being cut

away, so as to form an inclined face, a projecting portion on the other rail which overlaps the inclined face of the cut away portion of the ball of the first mentioned rail and which carries the wheel across the space between the rails, the inclined face of each rail extending to the end thereof.

2. A rail connection for railway tracks comprising two rails having their ends abutting, the abutting ends of the balls of said rails each having a face in a plane substantially at right angles to the rails and which extends part way across the rails, and an inclined face extending in an oblique direction across the remaining portion of the balls of the rails, said faces being separated when the rails are connected together so as to form a space made of two connecting sections, one section extending across the balls of the rails at right angles thereto, and the other section extending across said balls in an inclined direction.

3. A rail connection for railway tracks comprising two rails adapted to have their ends abut with a cross space between them,

the ends of said rails being uneven so that the cross space between them is divided into two sections, one section of said cross space extending at right angles part way across the balls of the rails, the other section of said cross space extending at an oblique angle across the remaining portions of the balls of said rails, the two sections connecting so as to form a continuous open cross space between the rails.

4. A rail connection for railway tracks comprising two rails adapted to have their ends abut with a space between them, one of said rails having a projecting part integral therewith connected to the ball and the base of said rail with a space between it and the web of the rail for a connecting plate between the rails, said projecting part overlapping a portion of the adjacent rail and carrying the wheel from one rail to the other.

Signed at Bremen, Germany, this 20 day of July, 1923.

ROBERT KUNICKE.
